J. DINKELACKER

HORSESHOE CALK

Filed July 21, 1921

Fig. 4.

Inventor
J. Dinkelacker.

By

Lacy & Lacy, Attorneys

UNITED STATES PATENT OFFICE.

JACOB DINKELACKER, OF HAZLETON, PENNSYLVANIA.

HORSESHOE CALK.

Application filed July 21, 1921. Serial No. 486,337.

To all whom it may concern:

Be it known that I, JACOB DINKELACKER, a citizen of the United States, residing at Hazleton, in the county of Luzerne and 5 State of Pennsylvania, have invented certain new and useful Improvements in Horseshoe Calks, of which the following is a specification.

This invention relates to an improved 10 horseshoe calk and has as one of its principal objects to provide a device of this character which will effectually prevent slipping of a horse when traveling over oiled roads or icy surfaces.

15 A further object of the invention is to provide a calk which may be readily applied and which, if desired, may be removed.

And the invention has as a still further 20 object to provide a calk employing a locking key for securing the calk in position upon the shoe and wherein the calk will be so formed that, when the key is applied, the key will be bent longitudinally and thus prevented from becoming accidentally 25 placed.

Other and incidental objects will appear hereinafter.

In the drawing:

Figure 1 is a perspective view showing a 30 horseshoe equipped with toe and heel calks;

Fig. 2 is a sectional view on the line 2—2 of Fig. 1, looking in the direction of the arrows;

Fig. 3 is a sectional view on the line 3—3 of Fig. 2, looking in the direction of the arrows; and

Fig. 4 is a sectional view on the line 4—4 of Fig. 1, looking in the direction of the arrows, this view showing a slightly different embodiment of the invention as comprehended in a heel calk.

Referring now more particularly to the drawing, I have shown my present invention in connection with a horseshoe 10 and shall first describe the invention as embodied in 45 a toe calk. An oblong base block 11 is employed and rising from said block is a sinuous calk member 12 preferably integral with the block. The block is provided with a flat bottom face to seat flat against the toe portion of the shoe and formed in the block at a point substantially midway between the ends thereof is a recess 13. Extending transversely through the block to intersect this recess is an opening having angularly 50 disposed portions 14 and 15 respectively, the portion 14 of the opening extending

obliquely with respect to the portion 15 and, as will be observed, the angularly disposed portions of the opening are formed to meet near one side face of the block. 60

Upstanding from the body block at opposite sides of the recess are studs 16 which snugly fit through openings formed in the toe portion of the shoe to accommodate the studs; and threaded through the shoe between said openings is a stud 17 snugly fitting in the recess 13 of the base block of the calk. The stud 17 is provided with an encircling groove 18 registering with the opening through the base block 11, and 70 driven through said opening to engage in said groove is a locking key 19. This key is preferably inserted in the portion 14 of said opening when, by pounding upon the key, the key is forced through the portion 75 15 of the opening. Thus, the key will, due to the angularity of the portions 14 and 15 of the opening, be bent longitudinally, and will thus be locked against accidental displacement from the opening. As shown in 80 Fig. 2, the key lies partly within the opening through the base block and partly within said groove 18. The key will thus effectually coat with the stud 17 for locking the calk upon the shoe, while the studs 16 will 85 coat with the shoe for sustaining shearing stress upon the calk. The calk will accordingly be firmly held in place. However, when desired, the key 19 may be removed and the calk displaced, the stud 17 being, 90 of course, also displaced.

In adapting the invention to a heel calk, a few slight structural changes are made. An oblong base block 20 is employed and rising from the block is a sinuous or S-shaped 95 calk member 21. The block is formed to seat flat against the shoe and is provided near one end with a recess 22. Extending from the block near its opposite end is a stud 23 snugly fitting through an opening provided in the shoe to accommodate the stud. Threaded through the shoe near said opening is a stud 24 having an encircling groove 25, and formed through the base block to register with said groove is an opening 26 intersecting said recess and having angularly disposed portions corresponding to the angularly disposed portions 14 and 15 of the opening of the toe calk. Driven 100 through the opening 26 is a key 27 locking the calk to the stud 24. Thus, as will be seen, the heel calk is substantially identical 105 110

with the toe calk with the exception that only one of the studs 23 is employed, while the recess 22 is arranged near one end of the base block instead of at a point substantially midway between the ends thereof as in the toe calk.

Having thus described the invention what is claimed as new is:

1. In a device of the character described, 10 a shoe stud, a calk fitting the stud, a key extending within the calk coacting with the stud locking the calk thereto, and means upon the calk bending the key whereby to lock the key against displacement.
- 15 2. In a device of the character described, a shoe stud, a calk fitting the stud and provided with an opening having angularly disposed portions, and a key extending within said portions of the opening and bent 20 thereby for locking the key against displacement while coacting with the stud and locking the calk thereto.
- 25 3. In a device of the character described, a shoe stud, a calk having a recess receiving the stud, the calk being provided with an opening intersecting said recess and having angularly disposed portions, and a key extending within said portions of the opening and bent longitudinally thereby for locking 30 the key against displacement while coacting with the stud and locking the calk thereto.

4. In a device of the character described,

a shoe stud having a groove therein, a calk having a recess receiving said stud, the calk being provided with an opening intersecting said recess to register with said groove and provided with angularly disposed portions, and a key extending within the angularly disposed portions of the opening bent longitudinally and engaging in said groove.

35

5. In a device of the character described, a shoe and calk one provided with a stud engaging the other and the latter provided with an opening having angularly disposed portions, and a key extending within the angularly disposed portions of said opening and bent thereby for locking the key against displacement while coacting with said stud for locking the parts together.

40

6. In a device of the character described, a shoe having an opening, a calk having a stud received in said opening and provided with a recess, a stud carried by the shoe and received in said recess, the calk being provided with an opening having angularly disposed portions, and a key extending within the angularly disposed portions of said opening and bent thereby for locking the key against displacement while coacting with the latter stud for locking the parts together.

45

In testimony whereof I affix my signature.

JACOB DINKELACKER. [L. S.]
